OF NEW YORK, N. Y., A CORPORATION OF NEW JERSEY.

FURNACE CHILL AND FLOOR-PIPE.

1,227,672.

Specification of Letters Patent.

Patented May 29, 1917.

Application filed January 15, 1917. Serial No. 142,342.

To all whom it may concern:

Be it known that I, WALTER S. ROCKWELL, a citizen of the United States, residing at 300 West One Hundred and Sixth street, 5 New York, county of New York, and State of New York, have invented certain new and useful Improvements in Furnace Chills and Floor-Pipes, fully described and represented in the following specification and the accompanying drawings, forming a part of 10 the same.

The invention comprises a water-box or chill located in the wall of the furnace opposite to and in a line with the charging-door, and employed as a means of connecting and circulating water through pipes laid upon the floor of the heating-chamber to support billets, ingots and other metallic objects, to facilitate their movement through 20 the chamber.

Such pipes in the present invention are extended in a straight line from the charging-door into tap-holes formed in the nearer side of the chill and screwed therein so that 25 water supplied to the chill circulates in the floor-pipe. The floor-pipes are connected with outlets, preferably outside the charging-door.

Where the furnace is heated by gas or 30 vaporous fuel, the chill may be located within the end wall of the furnace opposite to the charging-door, but when the furnace is heated by coal, the chill would be located in a bridge-wall extended transversely between the fire-box and the heating-chamber.

The connection of the pipes to the chill is, owing to the heat, liable to rust and deterioration, and by their extension from the charging-door directly to the chill, the floor-pipes can be readily disconnected from the 40 chill by grasping them, outside of the charging-door, and turning them to unscrew them from the tap-holes in the chill. To effect this, the pipes must be straight and rotatable.

In this construction, the tap-holes in the side of the chill are necessarily made at the level of the floor or piers upon which the floor-pipes rest, so that the pipes may extend in a straight line from the charging-door to the chill, which construction permits the pipes to be unscrewed from the chill when desired.

By their direct connection to the chill, the

floor-pipes when worn may be partially rotated in order to present to the ingots or billets new wearing surfaces, and thus prolong the life of the pipe.

Such straight pipes having threaded connections with the chill can obviously be unscrewed from the chill and new pipes substituted without cooling down the furnace.

This avoids the shutting down of the furnace and a long delay in cooling it off, which would be necessary if the pipes and chill were joined together by any complicated connections.

The invention will be fully understood by reference to the annexed drawing, in which Figure 1 is a plan in section on line 1—1 in 70 Fig. 2; Fig. 2 is a longitudinal section of the furnace taken adjacent to one of the floor-pipes; Fig. 3 is a similar section of a gas-heated furnace; Fig. 4 is a plan of the feeding-end of the furnace of Fig. 1; Fig. 5 75 is a transverse section of the chill and its connection with the floor-pipe by a plain tap-hole; and Fig. 6 is a similar view with a threaded bushing inserted in the chill and tapped to receive the end of the floor-pipe. 80

In Figs. 1 and 2, *a* designates the heating-chamber of the furnace which extends from the charging-door *b* to a bridge-wall *c* which divides the heating-chamber from a fire-box or combustion-chamber *d* in the end of 85 the furnace opposite to the charging-door *b*.

The fire-box is shown supplied with grates *d'*, a fire-door *e* and an ash-door *e'*, and the furnace is provided near the charging-door with spent gas outlet-flues *f*; and the heat 90 is circulated from the combustion-chamber through the entire length of the heating-chamber before the spent gases are discharged.

A table *g* is shown outside the charging-door *b* to support the ingots *h*, the table resting upon the sill *b'* of the charging-door *b*; and *i* represents a hydraulic pusher for propelling such ingots into the furnace, and pushing them through the heating-chamber to the bridge-wall, where they are removed by suitable means operating through a door *h* or *h'*.

The floor-pipes *l* are extended from the table *g* through the charging-doorway in a 100 direct line to the bridge-wall, the pipes being level with the top of the table, and resting upon the floor formed with numerous

piers *m* to support the floor-pipes, and heat the bottoms of the ingots.

A hollow chill-box *n* is shown built into the bridge-wall and its ends extended partly into the side-walls *a'* of the furnace, being thus enabled to strengthen and give a firm support to the bridge-wall.

The upper part of the chill extends above the level of the floor sufficiently to receive 19 tap-holes *o* in the side next the heating-chamber at the level of the floor, and the pipes, as shown in Fig. 5, are threaded to screw into such tap-holes and thus form a water connection with the chill.

Two of the floor-pipes are shown in Fig. 15 1, which number is sufficient to support one row or series of metal bodies while heating. A supply-pipe *p* is shown connected to the chill near the bottom and provided with a 20 valve *p'* to supply a flow of water through the chill and the pipes *l*. The pipes *l* outside of the charging-door *b* are arranged for connection to a suitable waste-pipe.

A union *s'* is shown in the pipe *l'*, to 25 connect the pipe *l* when its renewal is required; the front plate of the table *g* being notched, as shown at *g'* in Fig. 4, to permit the end of the pipe to be lifted for unscrewing the elbow, after which the pipe can be 30 unscrewed from the chill and a new one inserted.

Fig. 3 is a longitudinal section of a furnace-chamber *a²* heated by gas or vaporous fuel, a burner-inlet *r* being extended through 35 the end-wall *q* of the furnace for applying a burner at the end opposite the charging-door *b*.

In this construction, no bridge-wall is required, but the connection of the floor-pipes *l* with one another, and the supply of 40 liquid thereto, is provided by inserting a chill *n'* in the end-wall *q* of the furnace.

The tap-holes in the chill are at the level 45 of the pipes *l*, so that straight pipes can be extended from the door *b* of the furnace directly into the chill and screwed therein, or 50 unscrewed, without entering the heating-chamber, and this can be readily done when the furnace is hot if the water be shut off from the pipe *p*.

A side-door *k'* is shown in Fig. 3 to 55 discharge the ingots, billets, &c., from the rear end of the chamber when they have been gradually moved thereto. Such door *k'* also permits access to the floor-pipes where they enter the chill. A floor-pipe can thus be removed and another inserted without cooling or shutting down the furnace.

Access to the pipes where they enter the 60 bridge-wall, or end-wall, is also provided by the door *k* or *k'*, through which the pipes may be reached and manipulated by suitable tools without cooling off the furnace.

To render the joint between the pipe and 65 the chill more durable, I prefer to bush each

tap-hole in the chill, as shown in Fig. 6, by a screw-bushing *o'*, which is threaded to receive the end of the pipe, the same as the tap-hole *o* of Fig. 3.

Any number of floor-pipes can be connected with the chill in the same manner as the two which are shown herein, the chill simply requiring tap-holes to be made, in correspondence with the number of pipes, and in a line with the charging-doorway 75 through which the pipes are extended.

The introduction of water to a chill within a bridge-wall operates to materially lower the temperature of the bridge-wall and thus increase its durability.

The table *g* is shown on a level with the upper sides of the floor-pipes so that any object can be slid from the table to the pipes without obstruction, and such table is, in practice, extended to the doorway *b* and is 80 notched to clear the floor-pipes *l*.

It is immaterial how the exterior ends of the pipes be provided with suitable outlets; and it is also immaterial whether the chill be placed within a wall or not, as the 90 double-ended furnace-chamber heated by gas will require a bridge-wall, and in such case the chill could be located at the middle of the length of the chamber and floor-pipes 95 extended into its opposite sides from the doors at the opposite ends of the furnace.

Having thus set forth the nature of the invention, what I claim herein is:

1. A furnace having a heating-chamber with a charging-door at one end connecting 100 with the floor of said chamber, a chill located within the chamber opposite to the charging-door and extended above the level of the floor and having tap-holes therein at the floor-level, and straight floor-pipes extended from the said door directly into the chill and screwed therein so that they can be released from the chill by mere rotation.

2. A furnace having means at one end for heating the furnace-chamber, with a bridge-wall adjacent to such end and a chill within such bridge-wall, a charging-door at the opposite end of the furnace, and straight rotatable floor-pipes extended from the door directly into such chill.

3. A furnace having means at one end for heating the chamber, with a bridge-wall adjacent to such end and a chill within such bridge-wall, a charging-door at the opposite end of the furnace, and straight rotatable floor-pipes extended from the door directly into such chill and connected detachably thereto to facilitate renewal of the pipes.

4. A furnace having means at one end for heating the furnace-chamber, with a bridge-wall adjacent to such end, a charging-door at the opposite end of the furnace and the furnace-chamber extending from the door to the bridge-wall, a chill in the bridge-wall extended above the level of the said floor,

and floor-pipes extended into the bridge-wall and connected detachably to the chill at the level of the floor.

5. A furnace having a fire-box at one end with a bridge-wall adjacent thereto, a charging-door at the opposite end of the furnace with a furnace-chamber extending from said door to the bridge-wall, straight rotatable floor-pipes extended from the 10 charging-door into the bridge-wall and connected detachably to the chill at the level of the floor, and a discharge-door adjacent to the bridge-wall affording access to the pipes where they enter the same.
- 15 6. A furnace having means at one end for heating the furnace, with a bridge-wall adjacent thereto, a door at the opposite end of the furnace with a furnace-chamber extending from the door to the bridge-wall, a 20 chill in the bridge-wall extended above the level of the said floor, and provided with

tap-holes at the level of the chamber-floor, and floor-pipes extended from the door in a direct line to the chill and screwed into the tap-holes, means for supplying the chill 25 with water to circulate through the pipes, and the pipe having outlets outside of the said door.

7. A furnace having a heating chamber with a door at one end, means at the other 30 end for heating the furnace-chamber, and a bridge-wall adjacent to such other end; a hollow water-chill built within the bridge-wall and its ends extended into the side-walls of the furnace to support the bridge- 35 wall more rigidly, and straight rotatable floor-pipes extended from the door to the said chill, and water circulated through both the chill and the pipes.

In testimony whereof I have hereunto set 40 my hand.

WALTER S. ROCKWELL.
